US00D985883S

(12) **United States Design Patent** (10) **Patent No.:** **US D985,883 S**
(45) **Date of Patent:** **** May 16, 2023**

(54) **LEGGINGS FOR MEN**

(71) Applicant: **VIVRO INC.**, Seoul (KR)

(72) Inventors: **In-Woo Jo**, Seoul (KR); **Yong-Geun Jang**, Gimp'o-si (KR); **Seong Eun Baek**, Seoul (KR)

(73) Assignee: **VIVRO INC.**, Seoul (KR)

(**) Term: **15 Years**

(21) Appl. No.: **29/770,864**

(22) Filed: **Feb. 17, 2021**

(51) LOC (14) Cl. **02-02**
(52) U.S. Cl.

USPC **D2/731; D2/742**

(58) **Field of Classification Search**

USPC D2/742, 731, 728, 712
CPC A41F 9/007; A41D 27/22; A41D 1/06;
A41D 1/08
